[57] CLAIM

The ornamental design for a head for an insecticide application apparatus, as shown.

DESCRIPTION

FIG. 1 is a perspective view of a head for an insecticide application apparatus showing my new design;
FIG. 2 is an enlarged perspective view thereof;
FIG. 3 is a right side elevational view thereof;
FIG. 4 is a left side elevational view thereof;
FIG. 5 is a top plan thereof;
FIG. 6 is a bottom view thereof;
FIG. 7 is a front elevational view thereof; and,
FIG. 8 is a rear elevational view thereof.
The broken line showing is for illustrative purposes only and forms no part of the claimed design.
